UNITED STATES PATENT OFFICE.

CHARLES B. EDWARDS, OF WEYMOUTH, MASSACHUSETTS.

FEED-WATER REGULATOR.

SPECIFICATION forming part of Letters Patent No. 660,294, dated October 23, 1900.

Application filed July 31, 1900. Serial No. 25,374. (No model.)

To all whom it may concern:

Be it known that I, CHARLES B. EDWARDS, a citizen of the United States of America, and a resident of the city of Weymouth, county 5 of Norfolk, and State of Massachusetts, have invented certain new and useful Improvements in Feed-Water Regulators, of which the following is a specification.

This invention particularly relates to that 10 class of feed - water regulators especially adapted for use in connection with steam-boilers, and has general reference to all classes of feed-water apparatuses adapted for regulating the supply of fluid to a boiler, reservoir, 15 flushing-tank, or other analogous receptacle, whereby to maintain a predetermined fluid-level.

An object of the present invention is to provide a feed-water apparatus of simplified, 20 improved, and efficient construction and organization adapted automatically for controlling the supply of fluid to a receptacle and in which is employed two co-operative valves, one of which is fluid-actuated in its 25 movements and is normally subject to an excess of fluid-pressure at one end and the other of which is float-actuated and is adapted for nullifying and establishing the excess pressure on reciprocatory movements thereof, 30 whereby to effect an opening and closing movement of said fluid-actuated valve.

A further object of the invention is to provide in an apparatus of the class specified improved float-actuated valve mechanism including two concentrically-disposed valves, 35 one of which is normally retained in its closed position by an excess of fluid - pressure at one end and which controls the induction of feed-water to the boiler or receptacle and the 40 other of which operates in one direction to relieve the pressure at one end of said first-mentioned valve, whereby to permit the pressure at the opposite end of said valve to impart an opening movement thereto, and operates in an opposite direction to reestablish 45 this excess pressure to effect a closing movement of said first-mentioned valve.

With these objects in view the invention consists in certain details of construction and 50 in the combination and organization of the several elements, substantially as hereinafter

described, and more particularly pointed out in the claims.

In the drawings accompanying and forming part of this specification, Figure 1 is a 55 side elevation, partly in section, of a portion of one form of feed-water regulator or supply apparatus embodying the present invention. Fig. 2 is a central vertical section, on an enlarged scale, of a portion of the supply apparatus, showing a portion of a receiver and the valve mechanism in its normal closed position. Fig. 3 is a side elevation of the main or puppet valve that controls the fluid-supply; and Fig. 4 is a side elevation of a portion 60 of the float-actuated supplemental valve or tube-valve that controls the movements of the main valve.

Similar characters refer to like parts in all the figures of the drawings.

As a preamble to a detail description of the construction and organization of the several elements comprised in the feed-water regulator as a whole it is desired to state that the float-actuated valve mechanism which is 75 shown constituting an element of the apparatus illustrated in Fig. 1 may be used, as hereinafter described, in connection with a separate float-chamber or supplemental receiver or in direct connection with a main receiver 80 or boiler to which it is desired to supply fluid. Therefore it is not desired to limit the invention to the particular construction and organization of apparatus illustrated in Fig. 1.

In the preferred construction and organization thereof illustrated in Fig. 1 of the drawings the feed-water-regulating apparatus as a whole comprises a main receiver or boiler B; a supplemental receiver, float-chamber, or drum C, in communicating connection with 90 said main receiver; a valve-body D, shown supported on the supplemental receiver C and having two pressure-fluid chambers 2 and 2' and an outlet-chamber 3; means (shown as a supply-pipe 4) for supplying fluid to the two 95 pressure-fluid chambers 2 and 2' through the inlet-chamber 2, which is shown having communication with the chamber 2' through a conduit; an induction or feed pipe 5, connecting the outlet chamber or opening 3 with the 100 main receiver B; a duplex-valve device including a main valve E and a supplemental

valve F, disposed in relatively-concentric relation within the valve-body, and the main valve of which controls the admission of fluid from the inlet-opening to the outlet-opening and is normally subjected to an excess fluid-pressure at one end, which normally retains the same seated, and the supplemental valve of which is adapted for relieving or nullifying this excess pressure on one movement thereof to effect an opening movement of said valve and for reestablishing the excess pressure on another movement thereof to effect a closing movement of the main valve, and a valve-actuating float G, in adjustable connection with the supplemental valve.

The supplemental receiver or float-chamber C may be of any suitable general construction, may be supported in any suitable manner, and will preferably be connected to the boiler or main receiver B by pipes or conduits 6 and 6', which enter both receivers above and below the normal fluid-level thereof, so that a corresponding fluid-level will be maintained in both receivers.

The valve-body D, shown in Fig. 1 as supported on the crown or top plate of the supplemental receiver, embodies in the preferred construction thereof shown in Fig. 2 two pressure-fluid chambers 2 and 2', one of which constitutes an inlet or valve chamber and the other of which constitutes a piston-chamber of larger diameter than and is disposed, preferably, in vertical alinement with the inlet-chamber; an intermediate outlet or exhaust chamber 3, disposed in a plane substantially at right angles to and intersecting the common axes of the two pressure-fluid chambers; a valve-seat 7, having a valve-controlled opening 7' and disposed between the inlet and outlet chambers, and a conduit or passage-way 8, extending around the outlet-chamber and establishing communication between the two pressure-fluid chambers. The conduit or passage-way 8 between the two chambers 2 and 2' has its inlet and outlet ends in communication with said chambers above and below the upper and lower faces of the valve, respectively, irrespective of the position of said valve, so that pressure fluid will be conducted from the inlet-chamber to the piston-chamber to maintain a pressure at opposite ends of the valve, the effective pressure against the lower end of the valve being, when said valve is seated, considerably in excess of that against the upper end of the valve, whereby normally to retain the valve in its closed position and until the pressure is reduced below that at the upper end, as hereinafter described, to effect a closing movement of said valve.

As a convenient means for regulating the effective area of the conduit 8, whereby to determine the pressure of the fluid against the lower end of the valve, I have provided in adjustable connection with the valve-body and conduit a regulating device, which is shown in the nature of a needle-valve 9 in cooperative relation with one arm of the con-

duit and having a screw-threaded pin extending inward through a screw-threaded opening in the body and provided at the outer end thereof with a hand-wheel whereby the same may be turned in adjusting the valve.

The duplex-valve device consists in the preferred construction and organization thereof shown in Fig. 2 of two relatively-concentric valves E and F, respectively, the former of which controls the feed-water supply and will for convenience be herein referred to as the "main" or "fluid-actuated" valve, and the latter of which controls the movements of the main valve and will for convenience be herein referred to as the "supplemental" or "float-actuated" valve.

The main valve E, which is operated in its opening and closing movements by fluid and which is in the nature of a puppet-valve, has its valve-face 10, of relatively small area, in cooperative relation with the valve-seat 7 and has a diametrically-reduced tubular stem 12, with radial ports 12' preferably disposed to maintain constant communication between the outlet-chamber 3 and the interior of said valve-stem, and which stem has at the lower end thereof a piston 13, whose lower face is of relatively large area as compared with the effective area of the valve-face 10 and is disposed for reciprocatory movement in the piston-chamber 2', said piston being preferably formed integral with the valve-stem and having an axial opening registering with the axial opening of said stem. The valve E will preferably have radiating guides 14 at the upper end cooperating with the inner face of the valve-seat for directing the movements of this end of the valve.

It is desired to state in the above connection that the invention is not limited to the specific construction of main valve herein described, and illustrated in the drawings, as said valve is subject to various modifications within the purview of this invention.

The main valve E, which is operated in both directions by fluid, is so limited in its opening and closing movements with respect to the pressure-fluid chambers 2 and 2', as shown in Fig. 2, that the exit of the conduit will always be open to the piston-chamber to admit pressure fluid to the chamber 2' from the chamber 2 and below the lower end of the valve-piston whereby normally to retain the valve seated.

The supplemental valve F, which is in the nature of a tube-valve, has the upper end thereof extended through the piston into the stem of the main valve E, this end of the supplemental valve closely fitting the central opening in the main valve and having a central bore or recess 15, with one or more radial ports 16 at the lower or outer end thereof leading from the central bore to the outer face of the valve in position to communicate with the piston-chamber 2' and also having at the upper or inner end thereof ports 17,

leading from the central opening 15 preferably to an annular recess 18 in the periphery of the upper end of said valve and in position to communicate with the ports in the main-
5 valve stem during the descending movement of the supplemental valve to effect an opening movement of the main valve. In other words, the upper or inner end of the supplemental valve has port passages or conduits
10 adapted in one position of the supplemental valve for conducting the pressure fluid from below the piston end of the main valve to the outlet-chamber 3, whereby to relieve the excess pressure at this end and cause the fluid-
15 pressure above the valve to force said valve to an open position. It is desired to state in this connection that the invention is not limited to the specific construction of supplemental valve illustrated in the accompany-
20 ing drawings, as the same is subject to some modification so long as it embodies means for conducting fluid from the piston-chamber to the outlet-chamber of the valve-body, whereby to reduce the pressure at one end of the
25 main valve below that at the other end and effect an opening movement to said valve.

The supplemental valve F is shown having a stem 19, which extends through and below the valve-body into the receiver or float-
30 chamber and has adjustably secured at the lower end thereof a float G, shown as a hollow ball, which float constitutes the valve-
actuating means.

As a simple means for facilitating the ad-
35 justment of the float to determine the fluid-level in the receiver the valve stem or exten-
sion 19 is shown screw-threaded and extends into screw-threaded bosses on the float and is provided at the lower end thereof with a
40 packing-nut 19'. It will be obvious, how-
ever, that the means for effecting an adjust-
ment of the float to determine the movements of the valve E and the water-level may be variously modified without departure from
45 this invention.

In the form shown in Fig. 2 of the drawings the valve-body is provided with an externally-screw-threaded plug 21 at the lower end thereof, which has at the upper end thereof an annular wall which constitutes a part of the piston-chamber 2' and the upper end of which forms a seat for the piston and limits the opening movement of the main valve and which wall has openings through which pres-
50 sure fluid from the conduit 8 enters below said piston. This plug is shown screwed into a plate 23, riveted at 24 and 24' to the upper recessed wall of the receiver, said plate having a boss extending into said recess.

60 The means shown for attaching the valve-body to the receiver may of course be variously modified.

To permit the escape of any fluid which may have accidentally entered between the
65 end of the supplemental valve and inner wall of the main valve a vent 25 may be provided, as shown in Fig. 2. In the construction

thereof shown in Fig. 2 the lower ports 16 of the supplemental valve will be in constant communication with the piston-chamber irrespective of the position of the supplemental valve. In the normal position of the parts, as illustrated in Fig. 2 of the drawings, (the main valve being in its seated position and the supplemental valve being in its elevated 70 main-valve-seating position,) the upper ports 17 of the supplemental valve are out of register with the ports in the main-valve stem. Consequently the main valve is held in its seated position by the excess fluid-pressure 75 below the piston thereof. When the water-level in the float receiver becomes lowered, the float and connected supplemental valve will descend until the upper ports of said valve (which ports communicate with the 80 piston-chamber or high-pressure chamber below the main-valve piston through the central opening in the supplemental valve) come into register with the ports of the main-valve stem, which will permit the fluid under the 85 piston to flow through the central chamber of the supplemental valve into the outlet-chamber 3 of the valve-body, thus reducing the effective pressure below the piston suffi- 90 ciently to cause the then preponderant pres- 95 sure above to impart an opening movement to the valve to supply fluid to the receiver. When the water-level in the float-receiver rises sufficiently to impart a vertical move-
95 ment to the float, the tube or supplemental 100 valve will be elevated and will cut off com-
munication between the ports thereof and the ports in the main-valve stem, thus reestablishing an excess pressure in the piston-cham-
105 ber and causing the fluid at this end to impart a closing movement to the valve. From the foregoing it will be seen that the main valve is subjected normally, or when the valve is seated, to different fluid-pressures at oppo-
110 site ends and that by the ascending and de-
scending movements of the supplemental valve an excess pressure will be established first at one end and then at the other end of the valve to cause the fluid at these ends alternately to impart one an opening and the other a closing movement to the main valve. When the main valve is in its lowest or un-
115 seated position, it is practically balanced, as will be readily understood, so that imme-
diately upon the cutting off of communica-
120 tion between the piston-chamber and outlet-chamber by the ascending movement of the supplemental valve a sufficient excess of pressure will be established below the piston of the valve as compared with the pressure 125 at the opposite end of said valve to effect a quick-closing movement thereof.

I claim—

1. A feed-water regulator including a float-actuated valve having the opposite end faces 130 thereof of different areas; means supplying fluid to opposite ends of said valve whereby the valve will normally be retained in a closed position by the fluid at the large end thereof;

means including a float-actuated tube-valve in concentric relation with the fluid-actuated valve for alternately nullifying and establishing the effective pressure at the larger end of the valve whereby alternately to effect opening and closing movements to said valve.

2. The combination with a receiver, of a valve-body having an inlet and an outlet with an intermediate valve-seat; a puppet-valve 10 in coöperative relation with the valve-seat and having a tubular stem with ports leading therefrom to the outlet; means for supplying fluid to opposite ends of the valve whereby normally to retain the valve seated; 15 and a float-actuated valve extending into the stem of the puppet-valve and having ports disposed to relieve the pressure at one end of said valve on the descent of the float to effect an opening movement of the puppet-valve.
- 20 3. A feed - water regulator embodying a fluid-actuated valve having a piston of different effective surface area in fixed connection therewith; means for admitting fluid above the valve and below the piston; a concentrically-disposed tube-valve having ports disposed to conduct fluid from below the piston to a point above said piston; and float-actuated means for operating the last-mentioned valve.

- 30 4. A feed - water regulator embodying a valve - body having an inlet and an outlet chamber disposed with their axes in intersecting planes and having a piston-chamber of greater diameter than, and in substantial alinement with, the inlet-chamber; means for supplying fluid to the inlet and piston chambers; a puppet-valve for establishing communication between the inlet and outlet chambers and having a tubular stem with ports opening from the interior thereof to the outlet-chamber; a piston on the valve-stem working in the piston-chamber; a tube-valve extending into the puppet-valve and having exhaust-ports adapted, on one movement thereof, for establishing communication between the piston-chamber and outlet through the ports in the valve-stem whereby to reduce the pressure of the piston end of the valve to effect an opening movement thereof; and float-actuated means in connection with the tube-valve.

5. In an apparatus of the class specified a valve-body having an inlet-chamber and a piston-chamber of different diameters in substantial axial alinement and also having an exhaust or outlet chamber intermediate said inlet and piston chambers and disposed at right angles thereto; a valve-seat between the inlet and outlet chambers; a constantly-open fluid-passage leading from the inlet-chamber to the piston-chamber; a main valve coöperating with the valve-seat, and having a tubular stem with ports in constant communication with the intermediate chamber; a hollow piston at the end of the valve-stem seated in the piston-chamber; a tube-valve extending through the piston and into the valve-stem

and having ports for admitting fluid from the piston-chamber to the outlet-chamber; and a valve-actuating float in connection with the tube-valve whereby on the gravitation of the float the tube-valve will be moved to reduce the excess pressure at one end and effect an opening movement of the main valve.

6. In an apparatus of the class specified, the combination with a feed-conduit of automatically-operative valve mechanism including a main and a supplemental valve disposed in concentric relation, the former of which is fluid-operated in its movements and is normally subjected to fluid-pressure at both ends, and the latter of which is in the nature of a tube-valve and extends into and controls the movement of, the former; and a float in adjustable connection with the supplemental valve.

7. A feed-water regulator including a valve-body having two aligned pressure-fluid chambers of different diameters, an intermediate exhaust-chamber, and a conduit leading from one pressure-fluid chamber around the intermediate chamber to the other pressure-fluid chamber; a main valve disposed between the two pressure-fluid chambers and controlling the admission of fluid from one pressure-fluid chamber to the intermediate chamber; a supplemental tube-valve disposed, concentrically, within the main valve and effective on one operation thereof for admitting fluid from the other pressure-fluid chamber of largest diameter to the intermediate chamber whereby to relieve the pressure at one end of the valve and cause the fluid in the chamber of smallest diameter to effect an opening movement thereof; supply means in connection with one pressure-fluid chamber; and automatically-operative means including a float in adjustable connection with the supplemental valve.

8. In a feed - water - supply apparatus, a valve-body having an inlet and outlet opening; a valve-seat between said openings; a piston-chamber in alinement with the inlet-opening; a fluid-actuated main valve coöperative with the valve-seat and having a tubular stem provided with a piston located in the piston-chamber and also having ports disposed between the piston and valve and leading from the interior of the stem to the outlet-opening; a concentrically-disposed float-actuated valve extending into the stem of the main valve and having ports for establishing communication between the piston-chamber and outlet-opening of the valve-body through the ports in the main valve.

9. In an apparatus of the class specified, the combination of a boiler or main receiver; a supplemental receiver or float-chamber having a communicating connection with said main receiver; a float disposed in said supplemental receiver; a valve body or casing disposed outside of said supplemental receiver and having inlet and outlet openings separated by a valve-seat; a pipe leading to the

inlet-opening; a pipe leading from the outlet-opening to the main receiver; two concentrically-disposed reciprocatory valves, one of which is in the nature of a puppet-valve, is operated by fluid-pressure in both directions, and controls the supply to the main receiver, and the other of which is in the nature of a tube-valve and controls the operations of the puppet-valve; and an actuating-connector 10 between the tube-valve and the float.

10. The combination of a valve-body having a high and a low pressure fluid chamber and an intermediate outlet-chamber; a conduit extending around the intermediate chamber and maintaining constant communication between the two pressure-fluid chambers; supply means in connection with the low-pressure-fluid chamber; a puppet-valve normally cutting off communication between the 15 low-pressure-fluid chamber and the outlet-chamber; a tube-valve extending into the puppet-valve and normally cutting off communication between the high-pressure-fluid chamber and the outlet-chamber; ports in 20 said tube-valve disposed to establish communication between the high-pressure-fluid chamber and outlet-chamber on the descending movement of said tube-valve whereby to permit the pressure in the low-pressure-fluid 25 chamber to effect an opening movement of the puppet-valve; and means for actuating the tube-valve.

11. The combination with the valve-body having an inlet and an outlet opening separated by a valve-seat, and having a piston-chamber in alinement with the inlet-opening, of two relatively-concentric valves supported 30 in said body and one of which is controlled

in its movements by the other; a valve-actuating float in adjustable connection with one valve; and a conduit leading from the inlet-opening at a point above one valve around the outlet to the piston-chamber at a point below said valve. 40

12. The combination with the valve-body 45 having an inlet and an outlet opening separated by a valve-seat, and having a piston-chamber in alinement with the inlet-opening, of two relatively-concentric valves supported 50 in said body and one of which is controlled in its movements by the other; a valve-actuating float in adjustable connection with one valve; a conduit leading from the inlet-opening at a point above one valve around the outlet to the piston-chamber at a point be- 55 low said valve; and adjustable means for varying the effective area of the conduit.

13. An apparatus of the class specified comprising two communicating receivers; a float disposed in one of said receivers; feed-water- 60 supply means in connection with one of said receivers and including a valve-body, and two concentrically-disposed valves, one of which is subjected to fluid-pressure at both ends and the other valve of which has ports 65 for controlling the effective pressure of the fluid at opposite ends of the first valve to effect an opening and closing movement of said valve and has an operative connection with the float. 70

Signed by me at Boston, Massachusetts, this 24th day of July, 1900.

CHARLES B. EDWARDS.
